UNITED STATES PATENT OFFICE

ALBERT PERCY ROSANDER, OF FOREST PARK, AND FRANCIS PETER TIKALSKY, OF LA GRANGE, ILLINOIS, ASSIGNEES TO WESTERN ELECTRIC COMPANY, INCORPORATED, OF NEW YORK, N. Y., A CORPORATION OF NEW YORK

DIE CASTING MACHINE

Application filed April 24, 1930. Serial No. 446,824.

This invention relates to a die casting machine, and more particularly to the die charging and casting structure of a die casting machine.

5 The principal object of the invention is the provision of a die casting machine arranged with elements operating efficiently and at high speed to produce castings with accuracy and precision.

10 A feature of the invention is to provide an improved moving and supporting structure for the charging pot of a die casting machine.

15 Another feature of the invention is to provide a self adjusting joint structure for the compressed air inlet of the charging pot of the machine.

20 Another feature is to provide improved means for cooling the gate bushing.

25 Another feature is to provide fluid pressure means for advancing and withdrawing the casting cores to and from the dies.

30 A still further feature is to provide a yieldable connector in the structure for moving the charging pot to afford a resilient engagement of the molten metal conducting nozzle of the pot and the gate of the stationary die plate.

In accordance with the above object and 35 features, one embodiment of the invention comprises a die casting machine wherein the charging pot is positioned within a unitary carrier or receptacle which has a guideway on one side thereof which engages a guide bar for directing the charging pot in a vertical plane of movement, and an upright yoke adjustably hinged at its bottom to the sides of the casting machine furnace pivotally suspends the unitary carrier and charging pot

40 thereover. A connecting rod and crank reciprocate the carrier and swing the charging pot upon the upright yoke down into the furnace to fill the pot with metal. A spring pressed ball shaped joint structure is provided in the compressed air system for adjustably engaging the charging pot air nozzle, and a pair of compression springs are connected to the charging pot actuating rod

45 to effect a resilient connection of the metal conducting nozzle of the pot with the gate of

the stationary die plate. This gate is protected by a water cooled bushing having its water passageway extending back and forth along the metal conducting aperture thereof a plurality of times. The stationary die is 55 equipped with a pair of oppositely disposed movable cores mounted on its vertical edges and actuated by fluid operated pistons.

A clear understanding of one embodiment of the invention will be had from the following description thereof when taken in connection with the accompanying drawings, wherein

Fig. 1 is a plan view of the die charging end of a die casting machine;

Fig. 2 is a fragmentary side view of the same end with the charging pot in casting position;

Fig. 3 is a vertical cross-sectional view taken on the line 3-3 of Fig. 2;

Fig. 4 is a cross-sectional view of the adjustable joint structure for the compressed air nozzle of the charging pot;

Fig. 5 is an enlarged elevational view of the yieldable connector inserted in the charging pot actuating rod, partly shown in section;

Fig. 6 is an enlarged elevational view of the water cooled gate bushing;

Fig. 7 is an enlarged end view of the gate bushing with the right hand end cover thereof removed, taken on the line 7-7 of Fig. 6;

Fig. 8 is an enlarged side view of half the symmetrical core actuating structure, taken on the line 8-8 of Fig. 1;

Fig. 9 is a cross-sectional plan view of this core actuating structure, taken on the line 9-9 of Fig. 8, and

Fig. 10 is a fragmentary side view similar to Fig. 2 but with the charging pot in a retracted position.

Referring now to the drawings wherein like reference numerals designate the same parts throughout the several views, and particularly to Figs. 1, 2 and 3, there is disclosed the die charging end of a die casting machine, in connection with which the invented structure may be used and which end comprises a furnace 15 having a melting pot 16, adjacent which furnace is supported a sta-

tionary die plate 17. A stationary die 18 is secured to the die plate 17 and a movable die 19 is mounted on a movable die plate 20 which may be reciprocated by structure (not shown) to move the die 19 into and out of engagement with the die 18 during the casting operation.

The structure for moving and supporting the goose neck charging pot automatic pump 23 comprises a unitary carrier or receptacle 24 which has a pair of side arms 25—25, which with the aid of adjusting screws engage and support a cross rod 26 secured to a web or flange 27 of the charging pot. The pot is also supported by means of a lug 28 formed integrally with the back thereof and resting in a corresponding recess in the carrier 24. A hinge strap 29 bolted to the carrier 24 secures the lug 28 within this recess. A guideway 30 is formed integrally with one side of the carrier 24. An upright yoke 31 is pivotally bolted to the guideway 30 and to an offset portion 32 of the hinge strap 29 so that the carrier 24 may swing within this yoke. The bottom of the yoke 31 is pivotally pinned at each lower end thereof to a pair of links 33—33 which are pinned to U-shaped brackets 34—34 that are bolted to the sides of the top surface of the furnace 15. A pair of set screws 35—35 are provided in the ends of each link 33 to engage the top surface of the furnace 15 for adjusting these links and varying the height of the upright yoke 31. An actuating link 38 is pinned to the carrier 24 and connects with a crank 39 which is keyed to a cross-shaft 40 that is supported by brackets 41—41 at the end of the furnace. A guide bar 42 is formed integrally with a collar 43 which is freely rotatable on the shaft 40, and engages the guideway 30 for directing the movement of the carrier 24 when it is swung upon the yoke 31.

The self adjusting joint structure for the compressed air inlet of the charging pot 23 (as shown in Fig. 4) consists of a nipple 46 which is reciprocably mounted within a receptacle 47 projecting integrally from the stationary die plate 17. A pipe 48 leading from a source of compressed air (not shown) is threaded into the nipple 46, and a bushing 49 threaded into the receptacle 47 engages a ball shaped portion 50 of the nipple for holding it within the receptacle. The goose neck charging pot 23 is provided with a cover 51 which is secured by a clamp 52 to the lower portion of the charging pot, and this cover has a nozzle 53 threaded and locked to the outer end thereof for engaging the nipple 50. A coiled spring 54 is mounted within an aperture of the stationary die plate 17 and engages a plunger 55 which is provided with a spherical surface for engaging the ball shaped portion 50 of the nozzle 46, and a screw 56 forces the spring 54 into engagement with the plunger 55. With the joint

construction just described the connection between the nozzle 53 and the nipple 46 is made adjustable due to the spring 54, and compensates for any wear in the nozzle or nipple.

The gate bushing which the invention provides comprises (Fig. 6) a central cylindrical block 59 and two circular end cover plates therefor 60 and 61, this gate bushing being disposed within a recess of the stationary die plate 17 (Fig. 2) opposite a metal conducting nozzle 62 of the charging pot 23. The bushing has a central aperture 64 for conducting metal into the stationary die 18, and inlet and outlet water pipes 65 and 66 are threaded into the cover plate 61 and are connected with two circulating paths 67 and 68 (Fig. 7). The circulating path 68 makes four longitudinal traverses at the left hand side of the block 59 parallel to the aperture 64 and then connects with the pipe 66. The path 67 partially encircles the right hand end of the block 59 and then traverses the right hand side thereof four times parallel to the aperture 64, whence it connects with a passageway 69 which leads to the pipe 66. It will be understood that the covers 60 and 61 close the reversing or turning portions of the ends of these two traversing paths 67 and 68. It will also be noted that by longitudinally traversing the bushing a number of times through the paths just described, the circulating water tends to keep the bushing relatively cool.

The core actuating apparatus comprises a pair of shoulders 73—73 extending integrally from the sides of the stationary die 18, and a rectangular horizontally disposed core 74 (Figs. 8 and 9) is slidably mounted in a slot in each of these shoulders. Each core 74 has a collar 75 at its outer end for limiting its inward movement and an inner projecting portion 76 which cooperates with the movable die 20 to mold or cast a part or casting 77. The cores on both sides of the die are identical in construction and form identical castings and hence a description of one answers for a description of the other. In Fig. 9 it will be noted that the passage of the metal for forming each of the castings 77, only one of which is shown, since the other is located in the right half of the die, is through the aperture 64 of the gate bushing 59, where the metal forms a sprue 90, and the metal is then parted by a conical core 91 secured to the movable die 19 and flows into the casting cavities which form the parts 77—77. A casting rod 78 shouldered at 79 within each of the cores 74 extends inwardly therefrom for forming a central opening in the cast parts 77—77, and a plug 80 is threaded into the core 74 and abuts against the shoulder 79 to hold the rod 78 in position. The plug 80 is provided with a T-shaped head 81 which engages a corresponding slot in the head of a piston rod 82, which

is connected to a piston 83 mounted in a cylinder 84. Each cylinder 84 is supported by a pair of outwardly extending supporting plates 85 which are bolted to the shoulder 73 of the stationary die and to a cross block 86 forming the base of the cylinder 84. Inlet and outlet pipes 87 and 88 are connected to each cylinder 84 leading from a suitable, familiar four-way hand controlled valve (not shown) for simultaneously actuating both pistons 83—83 inwardly or outwardly to withdraw or force the cores 74—74, together with the casting rods 78—78 fixed thereto, into casting position.

15 The yieldable connector designed to move the charging pot 23 consists of two cross plates 93 and 94 (Fig. 5) which are secured respectively to connecting rods 95 and 96. The rod 95 is connected with the movable die 20 plate 20 through a reversing gear (not shown), and the rod 96 is adjustably pivoted to a crank 97 which rotates the shaft 40. A pair of bolts 98—98 provided with washers 99—99 at their right hand ends are secured to the plate 93 and extend slidably through apertures in the plates 93 and 94, and coiled compression springs 100—100 surround the bolts and extend from the plate 94 to the washers 99—99. Cylinders 101—101 are disposed around the springs between the plate 94 and the washers 99—99 to limit the amount of compression given the springs. The connecting rod 95 is provided with an extension 102 which engages a central longitudinal cavity in the rod 96 to maintain the two rods in alignment. When the rod 95 is moved to the left through its gear reversing connection (not shown) with the plate 20 the plate 93 slides the bolts 98—98 through the plate 94 to compress the springs 100—100 and thus resiliently drive the rod 96 which rotates the shaft 40, thereby providing a yielding connection between rods 95 and 96.

45 In the operation of the aforescribed structures it may at first be assumed that the charging pot 23 is located in the charging position, as shown in Figs. 1, 2 and 3. The spring 54 then maintains the nipple 46 in resilient engagement with the air nozzle 53, and the yieldable connector aforescribed, including the springs 100—100, then maintains the metal conducting nozzle 62 of the charging pot in resilient engagement with the gate bushing 59, since the shaft 40 which moves the charging pot through the intervention of the link 38 is actuated by the connector, and the connector at this time is being pulled to the left by the connecting rod 95. When the charging pot is in this charging position the dies 18 and 19 come into complete engagement with each other, and the cores 74—74 are moved inwardly preparatory to charging the dies. In order to move the cores inwardly the operator manipulates a hand controlled four-way valve (not shown) which causes

50 water or other fluid to enter the pipes 87 and exhaust from the pipes 88 connected to the pistons 84—84, thereby placing the cores in the position shown by the full lines in Figs. 8 and 9. Compressed air is then applied under control of a valve (not shown) to the pipe 48 connecting with the air nozzle 53, forcing molten metal from the charging pot 23 into the dies as shown in Figs. 8 and 9, to cast the parts 77—77. The cores 74—74 are next 70 withdrawn, or moved to the position shown in dot and dash outline in Fig. 8, by applying fluid pressure to the pipes 88—88, whereupon the castings are ejected or removed. In the 75 operation of the cores 74—74 it will be understood that the pistons 83—83 are simultaneously actuated by the fluid pressure, since both pistons are reconnected to the same controlling valve, and it will be noted that such fluid pressure operation readily serves the purpose 80 of withdrawing the cores.

20 The next step in the operation is the lowering and refilling of the pot 23 with metal, and this is accomplished by means of the connecting rod 96 which is moved to the right as the die plate 20 moves to the left in separating the dies. The aforementioned reversing gear (not shown) disposed between the die plate 20 and the rod 96 moves the rod 95 to the right as the die 20 is withdrawn from the die 19. The rod 95 then forces the connector plate 93 against the plate 94 and forces the rod 96 to the right, rotating the shaft 40 in a counter-clockwise direction and pulling the link 38 downwardly. The link 38 swings the charging pot carrier 24 in a counterclockwise direction upon its pivot points in the yoke 31, and swings the yoke 31 in a clockwise direction about its lower pivot points. Thus because the charging pot carrier 24 swings within the yoke and the yoke tilts to the right the charging pot 23 is lowered, and is refilled in the melting pot 16 by molten metal entering the nozzle 62 (Fig. 10). In raising the 95 charging pot to the charging position shown, the connecting rod 95 is moved to the left when the die 19 moves to the right for charging, and the link 38 causes the carrier 24 to pivot within the yoke 31 and moves the yoke 100 105 110 115 120 125 130 31 to the upright position shown.

40 It will be understood, of course, that the invention is not to be limited by the specific embodiment herein described and illustrated, but is to be limited only by the scope of the appended claim.

55 What is claimed is:

50 In a die casting machine, a furnace having a melting pot, a unitary inverted U-shaped supporting member having spaced arms hinged at their lower ends upon the furnace on opposite sides of the melting pot, a carrier pivotally supported at opposite sides upon said arms and having a U-shaped portion, a charging pot supported at three points upon said U-shaped portion of the carrier,

means for swinging the carrier and thereby
the supporting member to move the charging
pot into and out of the melting pot, and
guiding means for causing a predetermined
relative movement between the carrier and
the supporting member during the movement
of the carrier.

In witness whereof, we hereunto subscribe
our names this 15th day of April, A. D. 1930.

10   **ALBERT PERCY ROSANDER.**
                 FRANCIS PETER TIKALSKY.
